UNITED STATES PATENT OFFICE

JOHN ESLINGER, OF CHICAGO, ILLINOIS

AEROPLANE TOY

Application filed February 23, 1929. Serial No. 341,992.

This invention relates to improvements in aeroplane toys and more particularly to such toys arranged to be driven by electric motors.

The primary object of the invention is to provide a novel aeroplane toy which is driven from an external source of mechanical power such as an electric motor and adapted to simulate closely the action of a commercial aeroplane while traveling in a fixed path.

10 Another object is to provide an aeroplane toy having a miniature aeroplane mounted in such a way that part of its weight is counterbalanced, together with driving means capable of inducing a lifting action sufficient to 15 overcome the unbalanced weight of the aeroplane and to sustain such weight while the driving means is in operation.

Still another object is to provide a toy aeroplane of the above character having 20 means by which its lifting power may be varied at will to change the elevation at which the aeroplane flies under the power of its driving motor.

The invention also aims to provide a novel 25 toy aeroplane adapted for longitudinal tilting while flying and having means for stabilizing such action to maintain proper position of the plane.

Other objects and advantages of the invention will become apparent from the following detailed description taken in connection 30 with the accompanying drawings, in which

Figure 1 is a perspective view of a toy embodying the features of the present invention.

35 Fig. 2 is a side elevational view of an aeroplane to be used in the present toy, part of the plane being broken away to show certain of the parts in section.

Fig. 3 is a vertical sectional view through 40 the driving and supporting mechanism for the aeroplane.

Fig. 4 is a section taken along the line 4—4 of Fig. 3.

45 Fig. 5 is a fragmentary plan view of the aeroplane showing certain of the parts in section.

Fig. 6 is a sectional view taken along the driving shaft of the plane and showing a modified form of mounting for the plane.

50 While the invention is susceptible of vari-

ous modifications and alternative constructions, I have shown in the drawings and will herein describe in detail the preferred embodiment, but it is to be understood that I do not thereby intend to limit the invention 55 to the specific form disclosed, but intend to cover all modifications and alternative constructions falling within the spirit and scope of the invention as expressed in the appended claims.

The miniature aeroplane shown in the drawings to illustrate the present invention is of the monoplane type and made of thin sheet metal with a hollow fuselage 8, a wing 9 and a vertical rudder 10 of any preferred form. Wheeled struts 11 at the front of the fuselage support the forward end thereof in elevated position, as shown in Fig. 2, when the plane is resting on a flat surface. By forming the parts of the plane of sheet aluminum a plane 60 of extremely light weight may be provided.

The walls defining the forward portion of the fuselage are built around a frame structure 12 (Fig. 5) providing spaced bearings 75 for a short shaft 13 which projects forwardly and carries a propeller 14, by means of which the tractive effort of the plane is induced. The length of the propeller blades is such that the propeller will rotate freely 80 when the plane is traveling along a supporting surface.

Fast on the inner end of the shaft 13 is a beveled gear 15 which meshes with a gear 16 on an elongated shaft 17, one end of which is journaled at opposite sides of the fuselage in 85 the frame 12. The shaft 17 projects laterally from the fuselage a substantial distance in front of the center of gravity of the plane so that the weight of the rear portion of the plane tends to swing that portion downwardly about the shaft 17 as a fulcrum.

In the form of the invention shown in Figs. 1 to 5 the shaft 17 serves to sustain part of the weight of the plane and defines the path of movement thereof as well as to drive the 95 propeller 14 from an external source of power. To this end a long and relatively rigid shaft 17 is employed and the end thereof opposite the plane is rotatably supported by a platform 18 which is mounted interme- 100

diate its ends to pivot on a horizontal axis, thereby allowing for elevation of the plane and to rotate on a vertical axis thereby defining a circular path which the plane will traverse. Herein the shaft 17 is journaled at one end of the platform 18 in a bracket arm 19 upstanding therefrom and its end is attached by a suitable coupling 20 to the shaft of a small electric motor 21 which constitutes the source of motive power in the present instance. The motor is secured to the platform at the end opposite the bracket 19 so that the weight of the motor acts about a horizontal pivot of the platform 18 and through the medium of the shaft 17 to counter-balance the weight of the plane.

In the present instance the platform 18 is in the form of a substantially flat plate and is received in the closed upper end of a yoke member 22 which has two spaced legs 23 depending therefrom and supported on horizontal pivots provided by screws 24. The screws are entered through one of a plurality of vertical spaced holes in the legs 23 and extend into a block 25 rotatable about a tubular spindle 26 (Fig. 3) upstanding from and supported by a base 27 which is adapted to rest on a flat surface. To relieve friction a ball bearing 28 is interposed between the block 25 and the base.

To vary the proportion of the weight of the aeroplane which is counter-balanced by the weight of the motor 21, the platform 18 may be shifted longitudinally relative to the yoke 22 and clamped in the desired adjusted position by tightening a thumb nut 29 on a bolt 30 which projects through a longitudinal slot 31 in the platform and a hole in the yoke 22.

Electric current is conducted to the motor 40 from a source of power such as the secondary of a transformer 32 interposed between current carrying conductors 33 extending into the base 27. Within a recess 34 in the base one of the conductors 33 is connected to the lower end of the metallic spindle 26, the upper end of which has a wiping engagement with a contact strip 35 leading to a binding post 36 on the block 25. The other conductor is connected to a rod 37 insulated from and 50 extending through the spindle 26. A brush contact 38 bears on the upper end of the rod 37 and terminates in a binding post 39. The motor leads 40 are connected to the respective binding posts. As a means of varying 55 the speed of the motor and therefore the tractive effort of the aeroplane, a suitable rheostat 41 is interposed in one of the conductors 33.

The blades of the sheet metal propeller 14 60 may be twisted in a manner such that a tractive force acting to draw the aeroplane forwardly will be created upon rotation of the shaft 17 in the direction indicated by the arrow in Fig. 2. In such rotation the torque 65 of the shaft tends to tip the tail of the aero-

plane upwardly, but since the shaft 17 is journaled in front of the center of gravity of the aeroplane, the weight of the tail overcomes and substantially balances the tendency of the aeroplane to tilt in the rotation of the shaft 17. To stabilize this action and also cause the aeroplane to be maintained in horizontal position while flying, an elevating rudder or vane 42 is pivoted to the tail portion of the fuselage and may be shifted into different angular positions and maintained in such positions by means such as a swinging arm 43 secured to the fuselage and frictionally held in adjusted position. The rudder also serves to direct the aeroplane upwardly when the aeroplane is traveling along a supporting surface and the height to which the aeroplane rises under its lifting power may be determined by the angle to which the rudder 42 is set.

Instead of utilizing the drive shaft 17 to sustain part of the weight of the aeroplane and to define the path of movement thereof, the shaft may be flexible in character as indicated by the numeral 44 in Fig. 6. In this modification the shaft 44 extends through a tubular supporting member 45, one end of which is supported in spaced lugs 46 on the platform 18, the other end having a shoulder which is clamped by a cap 47 against a bracket 48 on the side wall of the fuselage 8. One end of the flexible shaft is coupled to the motor shaft while the other end is connected to a stub shaft 49 carrying the gear 16 which drives the propeller 14. It will be understood that the tube 45 supports the aeroplane in horizontal position so that the aeroplane is not free to tilt vertically as in the case of the construction shown in Figs. 1 to 5. With such an arrangement the elevating rudder 42 may be dispensed with or the mechanism for adjusting the rudder may be eliminated, the rudder being included in the aeroplane structure to give the aeroplane a realistic appearance.

To summarize the operation of the aeroplane in simulating the action of an aeroplane of commercial size, let it be assumed that the aeroplane and the base 27 are resting on a flat surface of sufficient size to enclose the circular path traversed by the aeroplane when travelling under its own power. Preferably the platform 18 is adjusted relative to the bracket 22 so that the weight of the aeroplane and the shaft 17 slightly overcomes the weight of the motor 21 which, acting about the horizontal pivot of the platform 18, exerts a counterbalancing action thereby enabling the aeroplane to rise when a lifting action is induced by the propeller 14 which is somewhat less than the lifting action which would be required to overcome the entire weight of the aeroplane.

When the motor is started, rotation of the propeller creates a tractive effort which draws

the aeroplane forwardly thereby causing it to travel about a vertical axis and in a circle the radius of which is determined by the length of the shaft 17. The rudder 42 cooperating with the upwardly inclined wing 9 of the aeroplane acts to lift the rear end of the fuselage 8 from the floor as the aeroplane moves forwardly. As soon as the proper speed has been attained the force of the air acting on the wing 9, the tail wing 9^a, and the elevating rudder will induce a lifting action sufficient to overcome the unbalanced weight of the aeroplane, whereupon the aeroplane will rise from its supporting surface to a level determined by the setting of the rudder 42. Inasmuch as the major portion of the weight of the aeroplane is counterbalanced, only a comparatively low speed need be attained to cause the aeroplane to rise from its supporting surface. Thus in the rotation of the propeller the aeroplane flies in a circular path several inches above the supporting surface and is maintained in horizontal position by the action of the rudder 42 combined with the unbalanced weight of the tail of the aeroplane 25 which counteracts the rotational torque exerted by the shaft 17 and tending to lift the tail upwardly.

By moving the arm of the rheostat 32, the speed of the motor may be varied at will to change the tractive effort and therefore the lifting action induced by the propeller. A decrease in the motor speed will cause the aeroplane to travel at a lower level, while the aeroplane will rise to a higher level when the speed is increased. Thus by manipulating the rheostat the true action of a commercial aeroplane may be simulated while the aeroplane travels in its predetermined path. 40 By utilizing the elevating rudder 42 to vary the level at which the aeroplane will fly, the operation of the toy aeroplane is made exceedingly realistic.

It will be noted that the horizontal pivot 45 provided by the screws 24 is spaced a substantial distance below the platform 18 on which the counterbalancing weight, that is the motor, is mounted. Thus, as the plane rises from the floor, the motor will move farther away from the pivot 24. The increase in the length of the moment arm of the counterbalancing weight causes the counterbalancing effect to be augmented automatically in proportion to the height to which the plane rises. This enables the plane 50 to fly at widely varying levels and overcomes the effect of centrifugal action which tends to maintain the counterbalancing weight and the plane at the same level.

55 I claim as my invention:

1. An aeroplane toy combining a base, a member supported by said base for pivotal movement about a horizontal axis and for rotation about a vertical axis, a miniature aeroplane, an elongated element mounted at one

of its ends on said member, the other end of said element being connected to and projecting laterally from said aeroplane whereby to permit elevation of the aeroplane about said horizontal axis and movement of the 70 aeroplane around said vertical axis as a center, and an electric motor mounted on said member and having a driving connection with a propeller on said aeroplane.

2. An aeroplane toy combining a miniature aeroplane having a driving propeller, an electric motor disposed remotely from said aeroplane and arranged to drive said propeller to induce a lifting action tending to elevate said aeroplane, and means 75 connected to said aeroplane and operable to define a circular path of movement therefor while permitting elevation of the aeroplane.

3. An aeroplane toy combining a miniature aeroplane having a driving propeller, 80 an electric motor disposed remotely from said aeroplane and arranged to drive said propeller to induce a lifting action tending to elevate said aeroplane, means connected to said aeroplane and operable to define a 85 circular path of movement therefor while permitting elevation of the aeroplane, and means by which the speed of said motor may be controlled to vary the lifting action of the aeroplane.

4. An aeroplane toy combining a miniature aeroplane arranged to travel in a predetermined circular path about a vertical axis, a propeller on said aeroplane rotatable to induce a lifting action on said aeroplane, 100 and an electric motor disposed externally of said aeroplane and adjacent said axis and arranged to drive said propeller.

5. An aeroplane toy combining a miniature aeroplane having a shaft projecting forwardly therefrom and carrying a propeller, a second shaft having one end projecting into the body of said aeroplane from the side thereof and geared to said first mentioned shaft, a member rotatably supporting the 105 opposite end of said second shaft, said member being mounted to swivel about horizontal and vertical axes to permit raising and lowering of the aeroplane and movement thereof in a circular path, and an electric driving motor for said second shaft mounted on said member on the side of said horizontal axis opposite said aeroplane whereby the weight of the motor will exert a counterbalancing 110 action on said aeroplane.

6. An aeroplane toy combining a base, a platform supported by said base to rotate about a vertical axis and to pivot about a horizontal axis, an electric motor mounted on said platform on one side of said horizontal axis, an elongated shaft having one end rotatably supported on said platform and coupled to said motor, a miniature aeroplane in which the other end of said shaft is journaled, the weight of said aeroplane act- 115 120 125 130

ing through the medium of said shaft serving to overbalance the weight of said motor, and means connecting said shaft to the propeller of said aeroplane.

7. An aeroplane toy combining a miniature aeroplane having a driving propeller, a member mounted to rotate about a vertical axis and adapted to swivel about a horizontal axis, means supported on said member and connected to said aeroplane to confine the movement of the aeroplane to a predetermined circular path, and an electric driving motor for said propeller mounted on said member on the side of said horizontal axis opposite said aeroplane whereby to counterbalance a portion of the weight of said aeroplane and thereby decrease the lifting action required to elevate the aeroplane under its own tractive effort.

8. An aeroplane toy combining a miniature aeroplane having a driving propeller, a member mounted to rotate about a vertical axis and adapted to swivel about a horizontal axis, means supported on said member and connected to said aeroplane to confine the movement of the aeroplane to a predetermined circular path, an electric driving motor for said propeller mounted on said member on the side of said horizontal axis opposite said aeroplane whereby to counterbalance a portion of the weight of said aeroplane and thereby decrease the lifting action required to elevate the aeroplane under its own tractive effort, and means for connecting said motor to a source of electric current including an adjustable rheostat for varying the speed of the motor and therefore the lifting action induced by the rotation of said propeller.

9. An aeroplane toy combining a miniature aeroplane having a power driven propeller, an electric motor located externally of said aeroplane for driving said propeller, means operable to cause said aeroplane to traverse a fixed circular path under the tractive effort of said propeller, and means normally acting to counterbalance a portion of the weight of said aeroplane.

10. An aeroplane toy combining a miniature aeroplane having a propeller, a member mounted for rotation about a vertical axis and for swiveling about a horizontal axis, power driving means carried by said member, an elongated substantially rigid shaft having one end rotatably supported on said member in substantially horizontal position and coupled to said driving means, the outer end of said shaft being journaled in the body of said aeroplane a substantial distance forwardly of the center of gravity thereof, and means providing a driving connection between said shaft and said propeller.

11. An aeroplane toy combining a miniature aeroplane having a propeller, an elongated shaft projecting laterally from and

journaled in the body of said aeroplane whereby to constitute a horizontal fulcrum about which the aeroplane may tilt vertically, means connecting said shaft to said propeller, a member rotatably supporting said shaft to permit said aeroplane to traverse a fixed circular path while resting on or flying about a supporting surface, driving means for said shaft disposed externally of said aeroplane, and an adjustable rudder on said aeroplane to stabilize the action resulting from the rotation of said shaft.

12. An aeroplane toy combining a miniature aeroplane having a propeller, an elongated shaft projecting laterally from and journaled in the body of said aeroplane whereby to constitute a horizontal fulcrum about which the aeroplane may tilt vertically, said fulcrum being located in front of the center of gravity of said aeroplane whereby the weight of the tail of the aeroplane acts in a downward direction to overcome the tendency of the rotating shaft to tilt the tail upwardly, means coupling said shaft to said propeller, means rotatably supporting the portion of said shaft located remotely from said aeroplane for movement about a vertical axis, and driving means for said shaft disposed adjacent said vertical axis.

13. An aeroplane toy combining a miniature aeroplane having a propeller, an elongated member projecting laterally from the side of said aeroplane and mounted to permit movement of the aeroplane around a vertical axis, means acting through the medium of said member to counterbalance a portion of the weight of said aeroplane including power operated means located externally of the aeroplane for driving said propeller to induce a lifting action on the wings of the aeroplane sufficient to overcome the unbalanced weight thereof and thereby cause the aeroplane to rise while rotating around said axis, and a movable vane on said aeroplane adjustable to different angular positions to determine the height to which the aeroplane will rise.

14. An aeroplane toy combining a base, a member supported by said base for pivotal movement about a horizontal axis and for rotation about a vertical axis, a miniature aeroplane, an elongated element mounted at one of its ends on said member, the other end of said element being connected to and projecting laterally from said aeroplane whereby to permit elevation of the aeroplane about said horizontal axis and movement of the aeroplane around said vertical axis as a center, a power driven propeller on said aeroplane for producing a tractive action for moving said aeroplane about said vertical axis and a lifting action tending to elevate said aeroplane about said horizontal axis, means exerting a counterbalancing ac-

tion on said aeroplane and mounted on said member above said horizontal axis so that the moment arm through which said counterbalancing means acts will increase automatically as said aeroplane rises in its flight.

5 In testimony whereof I have hereunto affixed my signature.
